UNITED STATES PATENT OFFICE.

JOESIRE S. ROGERS, OF LAURELHILL, FLORIDA.

PADLOCK.

1,153,405.

Specification of Letters Patent. Patented Sept. 14, 1915.

Application filed May 15, 1915. Serial No. 28,393.

To all whom it may concern:

Be it known that I, JOESIRE S. ROGERS, a citizen of the United States, residing at Laurelhill, in the county of Walton and State of Florida, have invented a new and useful Padlock; and I do hereby declare the following to be a full, clear, and exact description of the invention, such as will enable others skilled in the art to which it applies to make and use the same.

This invention relates to the art of locks and latches, and particularly to a new and useful padlock of the gear type.

An object of the invention is the provision of a padlock casing having a segmental gear bolt journaled therein, there being double means in the casing for locking the segmental gear bolt against being unlocked. However, after the gear bolt is unlocked the same may be operated to an open position by gear connections with a suitable key.

In practical fields the details of construction may necessitate alterations, falling within the scope of what is claimed.

The invention comprises further features and combination of parts, as hereinafter set forth, shown in the drawings and claimed.

In the drawings:—Figure 1 is a view in side elevation of the improved padlock. Fig. 2 is an edge elevation. Fig. 3 is a sectional view on line 3—3 of Fig. 2 showing parts in elevation, in other words showing the cover plate of a casing removed, and the riveted pins for securing the cover plate in place in section, and illustrating the segmental gear bolt locked in its closed position. Fig. 4 is a view similar to Fig. 3 showing the segmental gear bolt unlocked and thrown open. Fig. 5 is a sectional view on line 5—5 of Fig. 3. Fig. 6 is a sectional view transversely of Fig. 3 on line 6—6 thereof. Fig. 7 is a transverse sectional view on line 7—7 of Fig. 3. Fig. 8 is a detail perspective view of the segmental gear bolt, and the gears for operating the same, and illustrating the means for doubly locking the segmental gear bolt against being opened. Fig. 9 is a detail perspective view of an abutment dog, which must be first operated to unlock the segmental bolt. Figs. 10 and 11 are detail views of two keys to be used in conjunction with the lock for unlocking the same.

Referring to the drawings, 1 designates a

rectangular casing, but which may be any other desirable or suitable shape. This casing comprises a body 2 and a cover plate 3, which is secured to the body by means of riveted pins or the like 4. The body 2 is chambered or hollowed out to form a suitable pocket 5, the upper portion of which is semi-circular in contour as shown at 6, and journaled upon a pin 7 of the casing is a segmental gear member 8 having the gear teeth 9 and the semi-circular bolt 10.

In Fig. 3 the segmental gear member 8 is in a position so that the bolt 10 is locked, and in Fig. 4 the segmental gear member has been operated, therefore the bolt 10 is unlocked. The pocket 5 is provided with a plurality of offset recesses 11, 12 and 13. Loosely mounted upon a pin 14 in the recess 11, by reason of an elongated slot 15 is the shank 16 (in which the slot 15 is formed) of the abutment dog 17, which is provided with an abutment shoulder 18, which, before the dog is thrown outwardly toward the cover plate, lies in the path of the segmental gear member, therefore assisting in preventing the member from being actuated upon the pin 7. Secured in a recess 19 by means of small screws 20 is a leaf spring 21, the free end of which is forked as shown at 22, to straddle the pin 23, which passes through an elongated slot 24 of the dog, so that the dog may be moved toward the cover plate. The leaf spring 21 acts to hold the dog toward the segmental gear member, so that the shoulder 18 will be in the path of the edge portion 25 of the segmental gear member, to prevent it from being operated. The inner face of the dog beyond the shoulder 18 is provided with a curved cam cutaway portion 27, and extending outwardly from the portion 28 of the casing is a key pin journal 29 for the barrel 30 of the key 31. This key 31 is provided with a cam tongue 32, which, when the key 31 is turned, passes behind the dog and cams against the cutaway portion 27, thereby moving the dog toward the cover plate, against the action of the leaf spring 21, and moving the shoulder 18 from the path of the edge portion 25 of the segmental gear member, which may then be rotated, that is, when further unlocking.

Loosely journaled on the pin 23 behind the dog is a gear 34, which meshes with the

teeth 9 of the segmental gear member. Loosely journaled on a pin 35 is a gear 36 meshing with the gear 34, so that as the gear 36 is rotated in one direction or the other 5 the segmental gear member will be actuated, so as to open or close the bolt 10. Secured at 37 in the recess 12 (the bottom of which is not quite as deep as the bottom of the pocket 5 from where the pins 23 and 35 project) is a bar 38 having a slot 39, through which the pin 35 extends. This bar 38 extends behind the gear 36 and the segmental gear member 8, and the free end of the bar 38 is provided with a laterally extending lug 40, which engages a recess 41 on the inner face of the segmental gear member, thereby 15 additionally locking the segmental gear member against being actuated. A spring 43, which is secured at 44 in the recess 13, 20 acts to press the bar 38 and the gear 36 outwardly toward the cover plate, so as to hold the lugs 40 in the recess 41 of the segmental gear member. The free end of the leaf spring 43 has an elongated slot 45, through 25 which the pin 35 extends. The outer face of the gear 36 is provided with a slight recess 46, which partially surrounds the pin 35, to receive the barrel 47 of the key 48, whereas the projecting wings 49 of the key 30 barrel enter the lateral recesses 50 of the gear 36, and when the key 48 is so arranged to engage the gear, and subsequently to pressing against the gear to disengage the lug 40 from the recess 41 against the action 35 of the spring 43, the gear 36 may be rotated, which in turn will rotate the gear 34 and the segmental gear 8, that is, after the shoulder 18 has been moved from the path of the edge 25 of the segmental gear member. 40 When the segmental gear member is rotated in the direction of the arrow *a*, the bolt 10 is thrown open, and while being thrown open, the face (which is adjacent the cover plate) of the segmental gear member will 45 ride upon the enlarged portion of the dog, and the lug 40 will ride upon the opposite face of the gear member 8. When the segmental gear member is thrown in a reverse direction the bolt 10 is moved to a closed 50 position, in which case the shoulder 18 and the lug 40 respectively of the dog and the bar 38 will spring into locked engagement with the segmental gear member automatically. 55 The invention having been set forth, what is claimed as new and useful is:—

1. A padlock comprising a casing, a segmental gear member having a semi-circular bolt mounted in the casing for partial revolute movement, a spring retained dog having an abutment shoulder lying in the path of the segmental gear member to lock the same against movement, and gear connections adapted to be actuated by a member 60 for partially rotating the segmental gear

member when the shoulder is thrown from its path to unlock the bolt.

2. A padlock comprising a casing, a segmental gear member having a semi-circular bolt mounted in the casing for partial revolute movement, a spring retained dog having an abutment shoulder lying in the path of the segmental gear member to lock the same against movement, and gear connections adapted to be actuated by a member 65 for partially rotating the segmental gear member when the shoulder is thrown from its path to unlock the bolt, 70 a spring retained bar mounted in the casing and underlying one of the gears of said connections and provided with a lateral lug at its free end, said segmental gear member having a recess to receive said lug to additionally lock the segmental gear member, said connections when actuated by the member adapted to be 75 pressed by said member toward the back of the casing, and constituting means to withdraw the lug from the recess.

3. A lock comprising a casing, a segmental gear member including semi-circular bolt 90 mounted in the casing for a partial revolute movement, gear connections mounted in the casing to mesh with the segmental gear member and adapted to be actuated by a device, a spring retained bar underlying one 95 of the gears of said connections and having a lateral lug at its free end, said segmental gear member including a recess to receive the lug to lock the segmental gear member against partial movement, the gear under 100 which the spring retained bar lies adapted to be pressed toward the back of the casing by said device before being rotated by the device and constituting means to withdraw the lug from the recess.

4. A lock comprising a casing having a pocket provided with an upper semi-circular portion, a segmental gear member journaled in the semi-circular portion of the pocket for a partial revolute movement and 110 including a semi-circular bolt member, a pair of gears journaled midway of the pocket, one of which meshes with the segmental gear member, a dog loosely journaled in the casing for a slight movement laterally 115 to the casing, said dog having a shoulder lying in the path of one edge of the segmental gear member to lock the member, said dog adapted to be actuated laterally of the casing by a device to remove the shoulder 120 from the path of the segmental gear member, a spring retained bar underlying one of the gears of said path and having a lateral lug at its free end, a segmental gear member having a recess to receive the lug, the 125 gear under which the spring retained bar lies having means to receive a second device whereby the pair of gears may be actuated, and which gear under which the spring retained bar lies adapted to be pressed toward 130

the back of the casing against a spring of
said spring retained bar by said second de-
vice, and constituting means to actuate the
bar to withdraw the lug from the recess,
5 whereby the segmental gear member may be
actuated for opening the bolt.

In testimony whereof I have signed my

name to this specification in the presence of
two subscribing witnesses.
